UNITED STATES PATENT OFFICE.

WILLIAM B. HOUGH, OF CHICAGO, ILLINOIS, ASSIGNOR, BY MESNE ASSIGNMENTS, TO
PATENTED DEVICES COMPANY, OF PORTLAND, MAINE, A CORPORATION OF MAINE.

REINFORCED CONCRETE CONSTRUCTION.

1,173,109.

Specification of Letters Patent. Patented Feb. 22, 1916.

Application filed November 16, 1911. Serial No. 660,601.

To all whom it may concern:

Be it known that I, WILLIAM B. HOUGH, a citizen of the United States, residing at Chicago, in the county of Cook and State 5 of Illinois, have invented certain new and useful Improvements in Reinforced Concrete Construction, of which the following is a specification.

In constructing reinforced-concrete floors 10 and the like, the reinforcing bars or members should be secured at the desired distances apart and in the required horizontal plane before the concrete is poured.

The present invention relates to improved 15 means for thus securing and positioning the reinforcing members.

In the accompanying drawings, Figure 1 is a fragmental top plan view showing the decking or form-work upon which the concrete is to be poured, and representing several reinforcing bars as secured and spaced by means embodying my invention. Fig. 2 is a fragmental sectional view, illustrating the securing and spacing means in side elevation. Fig. 3 represents the securing and spacing means in edge elevation and in partial section. Figs. 4 and 5 are views similar to Figs. 2 and 3, respectively, but showing an alternative construction.

The decking is indicated at A and the reinforcing bars at B. These bars are supported at the desired distance from the lower side of the floor slab to be constructed, and at the desired distance apart, by means 35 including a plurality of stays or longitudinal members 1 each consisting of a metal strip, such as a strip of hoop iron; said strip being bent at intervals to form chairs 2 to support the bars B. These chairs may be of 40 any suitable shape or form. In Figs. 1, 2 and 3 each chair consists of a V-shape leg or gage 3 and two downwardly extending portions 4 at opposite sides of the leg 3, the portions of the longitudinal member 1 between the chairs being arranged to lie substantially flat upon the decking and being integrally connected with the lower ends 45 of the side portions 4.

The means for securing the bars B to the 50 chairs may be of any suitable character. The preferred construction consists in welding or otherwise affixing to each chair a strip 5 of sheet metal or other suitable material, the strip being secured at its mid-

portion to the chair, and the ends of the 55 strip being bendable to embrace the bar.

The bar-engaging or embracing means is welded at x and therefore bridges or connects the side portions of the leg or gage, thus strengthening the chair by preventing 60 said side portions from spreading and letting the bar down below its proper position.

It will be seen that the chair or longitudinal member is not weakened by cutting or punching bar-engaging arms therefrom; 65 thus the provision of separately-formed bar-gaging means welded or otherwise secured in place not only obviates impairment of the strength of the chair, but positively stiffens and reinforces it.

The device herein shown comprises a connected series of chairs. Figs. 1, 2 and 3 show the chairs as formed out of an integral strip of metal, but they may be otherwise connected. In Figs. 4 and 5 the chairs are 75 formed separately from, and welded or otherwise suitably attached to the longitudinal member 1^a at y. An advantage of the last mentioned construction is that the chairs may be conveniently spaced at any desired 80 distance apart, and at regular or irregular distances. A further advantage is that the portion of the longitudinal member 1^a below the chair ties the parts of the chair together and prevents spreading.

It will be understood that when separately 85 formed chairs are used, as in Figs. 4, and 5, the longitudinal member may be of any preferred material and form.

The feature of connecting together the 90 side portions of the leg or gage to prevent spreading of such side portions is claimed generically in my co-pending application Serial No. 658,683, filed November 6, 1911.

I claim as my invention:

1. A gage member for reinforced-concrete construction consisting of a metallic band having bar-supporting chairs attached to the band at intervals, each chair comprising a leg or gage extending downwardly to the 100 plane of the band and adapted to space a reinforcing bar from a form-work and two side portions at opposite sides of the gage, extending downwardly from the top of the gage to the plane of the band.

2. A gage member for reinforced-concrete construction consisting of a metallic band having bar-supporting chairs attached to

the band at intervals, each chair comprising a leg or gage extending downwardly to the plane of the band and adapted to space a reinforcing bar from a form-work, and two side portions at opposite sides of the gage, extending downwardly from the top of the gage to the plane of the band, and bar-engaging means attached to the upper part of the chair and adapted to strengthen the chair and prevent its sides from spreading apart.

3. A gage member for reinforced concrete construction, consisting of a metallic band forming a longitudinal connecting member and a series of reinforcing-bar-supporting chairs each connected to said member, each

of said chairs consisting of a folded leg or gage adapted to underlie and support a reinforcing-bar and to bear at its lower end upon a part so as to space the reinforcing-bar therefrom, and a pair of side portions at opposite sides of the gage, said side portions extending downwardly away from the upper portion of the gage and being connected to said longitudinal member. 20 25

In testimony whereof I affix my signature in the presence of two witnesses.

WILLIAM B. HOUGH.
